Oscar Geill

UNITED STATES PATENT OFFICE.

JAKOB DZIATKIEWICZ, OF PERTH AMBOY, NEW JERSEY.

CONTROL-VALVE.

1,233,654.

Specification of Letters Patent.

Patented July 17, 1917.

Application filed August 22, 1916. Serial No. 116,240.

To all whom it may concern:

Be it known that I, JAKOB DZIATKIEWICZ, a subject of the Emperor of Austria, and a resident of Perth Amboy, in the county of Middlesex and State of New Jersey, have invented certain new and useful Improvements in Control-Valves, of which the following is a specification.

This invention relates to improvements in means for preventing the overflow of bath tubs and has as its principal object the provision of means whereby the rising of the water in the tub automatically closes a valve at the terminal of the supply pipe, thus enabling a person to turn the water on and temporarily leave the same unattended.

This and other objects as simplicity, compactness and durability, are attained by the novel construction and combination of parts hereafter described and shown in the accompanying drawing, forming a part of this disclosure and in which:—

Figure 1 is a vertical sectional view taken through a conventional type of bath tub indicating the application of the invention.

Fig. 2 is an enlarged sectional view of the control valve, and

Fig. 3 is a similar sectional view showing a modified form of the control valve.

In the drawing the numeral 10 is applied to the bath tub resting upon feet 11 on its foundation and has leading to it a supply pipe 12 provided with a control valve 14 arranged in the faucet, or delivering element 15, which in this case is preferably provided with a screw threaded end 16 to which the device may be attached.

In the form shown in Fig. 2 the apparatus is seen to be composed of an upper hollow body 18 joined at its cylindrical lower end 19 by screw-threads to the lower element 20, the latter being bell-shaped at its bottom.

Formed integrally with this element is a disk 22 having a central circular opening 23, provided with a valve seat 24. Rising from the disk 22 are lugs 26 in which is pivoted a disk valve 27 by means of the pin 28, the same being so arranged that when in a raised position no obstruction is presented in the clear passage from the faucet through the apparatus.

Formed exteriorly of the bell shaped

lower portion are other lugs 30 in which is pivoted a lever 31, extending through the opening 32 and carrying a frame 33 containing a hollow spherical float 34. The outer end 35 of the lever 31 has pivotally engaged with it a link 38 connecting at its upper end with another lever 39, fulcrumed at 40 on the bracket arm 41, the lever extending into the body 20, through the opening 42 and being connected at its inner end with a link 43 engaged with lugs 44 attached to the lower side of the disk valve 27.

When the water rises in the tub 10 and before it reaches the height of the outlet pipe 45 it will cause the float to rise, and through the system of levers close the disk valve 27 upon the annular seat 24 effectually preventing a further inlet of water to the tub.

Thus one is enabled to turn on the water, either hot or cold or combined, as may be desired, and while preparing for the bath or occupied with other matters, allow the tub to be filled to a desirable height without danger of overflowing or wasting the water or drawing an undue quantity therein.

In the adaption shown in Fig. 3 the valve body 48 is shown to be somewhat different in shape, as is the lower element 49 secured by screw threads 50 and having a plate 52 provided with a central circular opening 53 adapted to be covered by the disk 55, hingedly engaged by a pin 56 to the lugs 57 formed with the plate 52 and operated through the link 59, the lower end of which is engaged with the inner end 61 of the lever 62, pivoted at 60 to the element 49 and engaged with a frame 63 carrying the float 34 as previously described.

The operation of the two structures shown are substantially the same and will be readily understood by the foregoing description taken in connection with the drawing.

Having thus described my invention what I claim as new and desire to secure by Letters Patent, is:—

In a device of the class described the combination of a faucet and float controlled means for stopping the flow of water therethrough comprising a hollow body member in screw threaded engagement with said faucet, and provided upon its lower interior face with screw threads, a second

hollow member secured by screw threaded engagement to said body member, a disk provided with an aperture formed integral with and adjacent to the top portion of 5 said second member, a valve seat formed in said disk, a valve disk pivoted upon said first mentioned disk and float controlled

means for opening and closing said valve disk as and for the purposes set forth.

Signed at New York, in the county of 10 New York, and State of New York, this 8th day of Aug. 1916.

JAKOB DZIATKIEWICZ.
